(57) **CLAIM**

The ornamental design for a furniture door with curtain, as shown and described.

DESCRIPTION

FIG. 1 is a front perspective view of a furniture door with curtain showing my new design;

FIG. 2 is a front perspective view of a chest of drawers including a furniture door with curtain showing my new design;

FIG. 3 is a front elevation view thereof;

FIG. 4 is a side elevation view thereof, the opposite side being a mirror image thereof;

FIG. 5 is a front perspective view of a furniture door with curtain showing a second embodiment of my new design;

FIG. 6 is a front perspective view of a chest of drawers including a furniture door with curtain showing the second embodiment of my new design;

FIG. 7. is a front elevation view thereof; and,

FIG. 8 is a side elevation view thereof, the opposite side being a mirror image thereof.

The subject matter shown in broken lines is for illustrative purposes only and forms no part of the claimed design.
